UNITED STATES PATENT OFFICE.

ARTHUR S. WHEELER, OF NEW YORK, N. Y., ASSIGNOR, BY MESNE ASSIGNMENTS, TO
VARIETYPER, INCORPORATED, A CORPORATION OF DELAWARE.

ESCAPEMENT MECHANISM FOR TYPEWRITERS.

Application filed May 28, 1926. Serial No. 112,364.

This invention relates to escapement mechanisms for typewriters and has for its primary object to provide improved power connections for an escapement shaft for controlling the movements of typewriter-carriages such, for example, as those employed in the Hammond typewriter.

One of the objects of the present invention is to provide a motor of improved construction whereby power may be applied to the escapement mechanism and related parts other than that derived from the motor which drives the carriage.

Another object of my invention is to provide improved winding mechanism for the auxiliary motor.

Other and further objects of invention will appear in the specification and be pointed out in the appended claims, reference being had to the accompanying drawings which show my invention in a preferred embodiment and in an adaptation to a Hammond typewriter.

In the drawings—

25 Figure 1 is a top plan view of my improved motor and self-controlled winding mechanism in connection with related parts of a Hammond typewriter, parts being broken away and parts shown in section;

30 Figure 2 is a section on the line 2—2, of Figure 1;

Figure 3 is a section on the line 3—3, of Figure 2;

35 Figure 4 is a section on the line 4—4, of Figure 1;

Figure 5 is a section on the line 5—5, of Figure 1, parts being broken away and parts shown in section;

40 Figure 6 is a similar section of some of the parts shown in Figure 5 in changed positions and with fragmentary portions of the spring-motor housing and driving connections shown above; and

45 Figure 7 is a fragmentary section taken on the line 7—7, of Figure 6.

Referring more particularly to the drawings, the typewriter frame 1 is provided with an upwardly presented lug 2 shown in dotted lines in Figure 5. Within this lug is journalled the rear end of an escapement shaft 3 to which the letter-space movements of the carriage are transmitted. Thus, referring to Figures 1 and 5 of the drawings, a main carriage-driving motor 100 is provided with a spring-driven gear 101 which

meshes into a rack-bar 102 (represented by broken lines) mounted on the carriage. Meshing with said rack-bar 102 and driven thereby is a spur gear 103 which is rigidly connected to a sleeve 104 which is freely journalled upon escapement shaft 3 and carries a ratchet 105. A pawl 106 is oscillatably mounted upon a stud 107 carried by a disc 108 and is held in engagement with said ratchet by means of a spring 109 which is secured at one end to a stud 110 carried by the disc 108. Said disc 108 is provided with a hub-portion 108^a which is non-rotatably connected to an escapement ratchet-wheel 5. For this purpose, said disc 108 and ratchet-wheel 5 may be keyed to the shaft 3 or these parts may be rigidly connected together by a common sleeve and freely journalled upon said shaft 3. The ratchet wheel 5 is adapted to be engaged by a pawl 6 pivoted at 7 upon a hammer-constraining lever 8, said lever being freely pivoted on the escapement shaft 3 and provided with a bent tail lever 9 which as shown in Figure 1 is provided with an enlargement 10 which moves upwardly and downwardly upon a stud 11 which, as shown in Figure 5, may be locked in any suitable position by a set screw 12, the lower position of a hammer bar 13 being thereby determined. Inasmuch as the spring-pressed pawl 106 is included in the driving connection between the carriage-driving motor and the escapement shaft 3, a return or retrograde movement of the carriage is provided for without a corresponding movement of said escapement shaft 3. As shown in Figure 5, an escapement beam 14 which oscillates on a pivot 15, carries an arm 16 provided with a slot 17 within which is disposed a pin 18 carried by the pawl 6 and by means of which said pawl is moved into and out of engagement with ratchet 5. A detent 19 mounted in one arm of the beam 14, is adapted to engage the teeth of ratchet 5 as pawl 6 is retracted from said ratchet. The foregoing parts are in general use on the Hammond typewriter at the present time.

By an inspection of Figure 5, it will be understood that whenever a typewriter key is depressed, the resulting clockwise oscillation of escapement beam 14 operates to retract the pawl 6 from engagement with ratchet 5. This movement thus releases the hammer-operating lever 8 and permits the actuation of the hammer bar 13 in a well-

known manner. At the same time, the detent 19 is moved into engagement with ratchet 5 which however is immediately disengaged therefrom by the return or counter clockwise movement of escapement beam 14 which returns the pawl 6 to ratchet-engaging position and thus serves to apply power from ratchet 5 to lever 8 for retracting hammer bar 13 to normal position.

10 As heretofore constructed, typewriting machines of the Hammond type in which the escapement mechanism has derived its power solely from the spring motor which drives the paper-carriage, it has been necessary to 15 provide an excessively heavy tension in the spring of said motor in order to supply the required amount of power for returning the hammer bar to normal position after each 20 operation thereof. Such a construction has heretofore made necessary a heavier carriage as well as sturdier operating connections therefor.

According to my improved construction shown and described in the present application, it becomes possible to employ a lighter carriage and less tension in the spring motor which drives the carriage so that a lighter 25 running and more easily operated machine is made possible. For this purpose, I employ 30 the auxiliary power mechanism now to be described.

Mounted upon the rearmost end of escapement shaft 3 is a spur gear 20 which meshes into a larger spur gear 21, said larger gear 35 being secured to the drive shaft 22 of an auxiliary motor by means of a set screw 23. The essential purpose of this auxiliary motor resides in the provision of suitable power outside of the carriage driving motor for 40 retracting the typing hammer after each typing operation. By means of this provision it becomes possible to employ a carriage-driving motor of less power and lighter action so that the return or retrograde movements of the carriage can be had 45 more expeditiously and with less effort. As shown in Figures 1, 4, and 5, said drive shaft 22 is journalled in oppositely arranged plates or frames 24 which are rigidly secured 50 to the typewriter frame 1. Journalled upon an enlargement 25 of the shaft 22 is a housing 26 within which is disposed a coiled spring 27. The inner end of said spring is secured at 28 to said enlargement 25, the 55 outer end of said spring being secured by a screw 29 to the peripheral wall of the housing 26. Said housing is provided with a circular rack 30 with which meshes a worm screw 31. As shown best in Figures 1 and 6, 60 the worm screw is carried by an extension 32 of an armature shaft 33 of an electric motor 34, said extension 32 being yieldably connected to the section 33 by means of a coiled spring wire 34'. Projecting rearwardly 65 from the lateral surface of spur gear 21 is a

pin 35 which during a continued step by step movement of spur gear 21, is brought into engagement with an arm 36 of a star wheel 37, said star wheel being secured to a rotary shaft 38 by means of a set screw 39. 70 The shaft 38 is journalled at opposite ends in the frames 24 as shown best in Figure 2. As shown in the preferred embodiment, the star wheel carries four arms of which the two oppositely presented arms 36 are arranged adjacent to the path of pin 35 as it revolves with gear 21. The other two arms 40 project substantially at right angles to the arms 36 and are axially spaced therefrom so that their revolving movements 75 bring them into the path of a pin 41 which projects forwardly from the lateral wall of spring housing 26. As shown best in Figures 5 and 6, a leaf spring 42 which is secured to a cross bar 43 by means of a screw 44, is presented upwardly into position to interlock yieldably with any one of a series 80 of star pointed cam arms 45 which are secured to the shaft 38 in such a way as to lock said shaft in position when not positively engaged by one or the other of pins 85 35 and 41.

Referring now to Figures 2 and 3, the shaft 38 is provided at one end with a diametral slot through which passes a metal strip 46, the outer ends 47 of said strip being bent around on the periphery of the reduced end of shaft 38 to adapt said strip to bridge the space between oppositely arranged 90 spring contacts 48 in every other position of the star wheel 37. Secured to the spring contacts 48 are wires 49 which, as indicated in Figure 1, are contained in a cable 50, said cable having a branch 51 leading to motor 34. It is obvious, therefore, that whenever 95 the strip 46 is in circuit-closing position, the motor 34 will be energized and the spring 27 will be wound. The cable 50 may be provided with suitable socket connections 100 whereby the motor 34 may be connected up 105 with an ordinary lamp socket.

It will be understood from the above description that as the escapement mechanism is operated step by step during the use of the typewriter, the spring 27 is transmitting 110 power to the drive shaft 22 in such a way as to enable the employment of a weaker spring upon the carriage of the typewriter and thus provide a lighter action of the carriage without in any way adversely affecting 115 the typing action. It will be understood that as the pin 35 revolves, the star wheel 37 will be rotated into position to close the circuit through motor 34 and as the spring 27 is wound up, the pin 41 carried by the housing 26, will impart a further movement to star wheel 37 which action breaks the circuit of motor 34.

Referring now to Figure 1, an interlocking arm 52 is loosely mounted upon the 120

drive shaft 22, said arm being provided with a laterally presented finger 53. As shown in Figure 7, a bent plate 54 is secured by a stud 55 to the gear 21, the outwardly deflected edge of plate 54 being adapted to engage the finger 53 during rotation of gear 21. Projecting laterally from the wall of housing 26 is a pin 56 which, when the motor 34 is deenergized, constitutes a fixed stop. It may be seen, therefore, that if at any time, the current is completely cut off from motor 34 for a sufficient length of time during the use of the typewriter, the bent plate 54 will be revolved by the movement of gear 21 until it comes into engagement with the radial arm 52 which will be revolved until it comes into the position shown in Figure 6 in which it abuts against the stop pin 56. The advantage of this device will be seen in the event, for example, that the current having been turned off at the lamp socket, such as may occur at night, a subsequent use of the typewriter may take place without the switch being turned to closed position, whereupon the operation just described would take place.

I claim:

1. In a typewriter, the combination with a carriage-driving motor, of escapement mechanism connected thereto, a hammer-constraining lever connected to said escapement mechanism, and an auxiliary motor connected to said hammer-constraining lever through said escapement mechanism.
2. In a typewriter, the combination with a carriage-driving motor, of escapement mechanism connected thereto, a hammer-constraining lever connected to said escapement mechanism, an auxiliary motor connected to said hammer-constraining lever through said escapement mechanism, and means under the control of said auxiliary motor for reenergizing the latter.
3. In a typewriter, the combination with a hammer-constraining lever, of carriage-escapement mechanism including a ratchet-wheel, a spring motor geared to said ratchet-wheel, said spring motor comprising a rotary shaft, a rotary housing coaxial with said shaft and a coil spring having its opposite ends secured to said rotary shaft and housing respectively, a pawl mounted on said lever and engaging said ratchet-wheel, means for moving said pawl into and out of engagement with said ratchet, and means under the control of said rotary shaft and housing for rotating the latter.
4. In a typewriter, the combination with a carriage-driving motor, of a carriage-rack geared thereto, a hammer-constraining lever, escapement mechanism connecting said rack to said hammer-constraining lever, and an auxiliary motor connected to said hammer-constraining lever through said escapement mechanism.
5. In a typewriter, the combination with an escapement shaft, of a vibratory lever, a hammer connected to said lever, escapement mechanism for controlling the escapement movements of said shaft, said escapement mechanism including a pawl and ratchet connection between said shaft and lever, a motor geared to said escapement shaft, an electric motor geared to the first-mentioned motor, an energizing circuit for the second-mentioned motor including a switch for making and breaking the energizing circuit, a star-wheel for operating said switch, and means operated by the first-mentioned motor for imparting a step by step movement to said star-wheel.
6. In a typewriter, the combination with an escapement shaft, of a carriage-driving motor, a one-way driving connection between said motor and shaft, a lever oscillatable about the axis of said shaft, a hammer connected to said lever, a ratchet keyed to said shaft, a pawl pivotally connected to said lever and operably engaging said ratchet, an escapement beam controlling the escapement movements of said shaft and moving said pawl into and out of engagement with said ratchet, said pawl when disengaged from said ratchet being adapted to permit the printing stroke of said hammer, and when thrown back into engagement with said ratchet to retract said lever and hammer to normal position, and an auxiliary motor geared to said escapement shaft independently of said one-way driving connection.
7. In a typewriter, the combination with a hammer-operating lever, of carriage-escapement mechanism operably connected thereto, and a spring motor operably connected to said lever through said escapement mechanism, said spring motor including a rotary shaft, a rotary housing, and a coil spring having its opposite ends secured to said housing and shaft respectively, and means for rotating the housing to rewind the spring when said housing and shaft reach a predetermined position in their relative rotation.
8. In a typewriter, the combination with an escapement shaft, of a carriage-driving motor, a ratchet-drive connection between said motor and shaft, a hammer-returning lever oscillatable about the axis of said shaft, a ratchet wheel keyed to said shaft, a pawl pivotally connected to said lever and operably engaging said ratchet-wheel, an escapement beam controlling the escapement movements of said shaft and moving said pawl into and out of engagement with said ratchet-wheel, said pawl when in engagement with said ratchet-wheel being adapted to restrain the hammer from its printing stroke and when disengaged from said ratchet-wheel to permit the printing stroke of said hammer, and an auxiliary motor geared to said escapement shaft independ-

ently of said ratchet-drive connection and adapted to supplement the power applied to said shaft by the carriage-driving motor.

9. In a typewriter, the combination with 5 an escapement shaft, of a spring motor comprising a drive-shaft provided with a gear geared to said escapement shaft, a rotary housing coaxial with said drive-shaft, a coil spring arranged in said housing and having 10 its opposite ends secured to said drive-shaft and housing respectively, an electric motor having an armature shaft geared to said housing, a switch for said electric motor, a star-wheel for operating said switch, a pin 15 carried by said drive shaft gear for operating said star-wheel, and a pin carried by said housing for operating said star-wheel.

10. In a typewriter, the combination with 20 an escapement shaft, of a spring motor comprising a drive-shaft, a gear keyed to said drive-shaft and geared to said escapement shaft, a rotary housing coaxial with said shaft, a coil spring arranged in said housing and having 25 its opposite ends secured to said rotary shaft and housing respectively, an electric motor having an armature shaft geared to said housing, a switch for said electric motor, means operated by said gear and rotary housing for operating said switch 30 to start and stop said electric motor, a laterally presented stop pin carried by said housing, a laterally-projecting stop-plate mounted on said gear, and an arm movable on said drive-shaft and interposable between 35 said stop-pin and stop-plate for locking said drive-shaft.

11. In a typewriter, the combination with 40 an escapement shaft, of a spring motor comprising a rotary shaft geared to said escapement shaft, a rotary housing coaxial with said shaft, a coil spring arranged in said housing and having its opposite ends secured to said rotary shaft and housing respectively, an electric motor having an armature shaft geared to said housing, a switch for said electric motor, means operated by the rotary shaft of said spring motor for operating said switch to start said electric motor and by said rotary housing for 45 stopping said electric motor, said armature shaft comprising yieldably connected sections.

12. In a typewriter, the combination with 55 a carriage-driving motor, of an escapement shaft, means including a pawl and ratchet connection for connecting said motor to said shaft, a vibratory hammer-constraining lever, escapement-control means including a releasable connection between said shaft and lever, and auxiliary power means geared to 60 said escapement shaft independently of said pawl and ratchet connection.

13. In a typewriter, the combination with a carriage motor, of an escapement shaft, a

one-way driving connection between said 65 motor and shaft, a lever pivoted on said shaft, a ratchet wheel keyed to said shaft, a pawl pivotally connected to said lever and normally engaging said ratchet-wheel, an escapement lever movably engaging said 70 pawl, a dog movable by said escapement lever into and out of engagement with said ratchet-wheel, auxiliary power means geared to said escapement shaft, independently of said one-way driving connection, and a 75 hammer connected to the first-mentioned lever and returnable to normal position by said ratchet when said pawl is thrown into engagement with said ratchet.

14. In a typewriter, the combination with 80 a carriage-driving motor, of an escapement ratchet-wheel, means including a one-way driving connection for connecting said motor to said ratchet-wheel, a typing hammer, 85 means including a pawl which releasably engages said ratchet-wheel for connecting said typing hammer thereto, an escapement beam movably engaging said pawl and carrying a ratchet dog for engaging said ratchet at 90 times when said pawl is moved out of engagement therewith, and an auxiliary motor geared to said ratchet-wheel independently of said one-way driving connection.

15. In a typewriter, the combination with 95 a carriage-driving motor, of escapement mechanism therefor, means including a one-way driving connection for connecting said motor to said escapement mechanism, a typing hammer operably connected to said escapement mechanism, and an auxiliary 100 motor connected to said escapement mechanism independently of said one-way connection.

16. In a typewriter, the combination with 105 the rack of a reciprocatory carriage, of a carriage-driving motor, a vibratory hammer-operating lever, an escapement ratchet-wheel, a mechanical train including a pawl and ratchet connection for connecting said rack to said ratchet-wheel, a pawl pivotally mounted on said hammer-operating lever and operably related to said ratchet-wheel, a ratchet-dog for engaging said ratchet alternately with said pawl, means for moving 110 said pawl and dog into and out of engagement with said ratchet-wheel, and an auxiliary motor geared to said ratchet-wheel. 115

17. In a typewriter, the combination with 120 an escapement shaft, of a carriage-driving motor, means for connecting said motor to said shaft, escapement mechanism connected to and controlling the escapement movements of said escapement shaft, a hammer-operating lever, an auxiliary motor, and means including portions of said escapement mechanism for connecting said auxiliary motor to 125 said hammer-operating lever.

ARTHUR S. WHEELER.
